ATTORNEY.

UNITED STATES PATENT OFFICE.

WILLARD T. SEARS, OF MONTCLAIR, NEW JERSEY, ASSIGNOR TO NILES-BEMENT-POND COMPANY, OF NEW YORK, N. Y., A CORPORATION OF NEW JERSEY.

RATCHET-AND-PAWL MECHANISM.

Application filed September 1, 1922. Serial No. 585,805.

To all whom it may concern:

Be it known that I, WILLARD T. SEARS, a citizen of the United States, residing at Montclair, in the county of Essex and State 5 of New Jersey, have invented certain new and useful Improvements in Ratchet-and-Pawl Mechanism, of which the following is a specification.

This invention relates to a ratchet and 10 pawl mechanism and in particular to mechanism of this type for use in connection with a feed mechanism for machine tools.

An object of the present invention is to provide a ratchet and pawl mechanism 15 which will permit variation of the feeding action of a ratchet wheel within fine limits.

Another object of the invention is to provide a particular form of pawl as a part of the feeding mechanism which may be disengaged from its ratchet wheel at any point 20 in its operative stroke with a minimum of resistance.

One feature which enables me to accomplish the above named objects is that the 25 pawl comprises two members pivotally connected together and held, by means of a spring, in relative operative position.

Another feature which is advantageous is that the pawl may be disengaged from the 30 ratchet wheel by engagement of an intermediate pawl member with an adjustable stop which oscillates this intermediate pawl member and permits the other pawl member to oscillate relative to the first pawl member and thus disengage itself from the 35 ratchet wheel.

With these and other objects in view, my 40 invention consists in the features of construction and operation set forth in the following specification and illustrated in the accompanying drawing.

In the accompanying drawing annexed hereto and forming a part of this specification, I have shown my invention embodied 45 in a mechanism for slowly rotating a shaft but it will be understood that the invention can be otherwise embodied and that the drawing is not to be construed as defining or limiting the scope of the invention, the 50 claims appended to this specification being relied upon for that purpose.

In the drawing:

Figure 1 is a front elevation of the complete mechanism forming the present invention, and

Fig. 2 is a central vertical section of the same.

In the above mentioned drawing, I have shown but one embodiment of the invention which is now deemed preferable, but it is to be understood that changes and modifications may be made within the scope of the appended claims without departing from the spirit of the invention.

Briefly, my invention in its broadest aspect 65 comprises the following principal parts: first, a rotating shaft which may be suitably supported and which it is an object to slowly rotate in a step-by-step manner; second, a ratchet wheel fastened directly to said shaft, 70 third, an oscillating arm; fourth, a reciprocating rod attached to said arm whereby the arm may be oscillated through a constant angular distance with each movement of the rod; fifth, a pawl of novel construction 75 having two pivotally connected members, one of which is adapted to engage the ratchet wheel; sixth, an adjustable stop positioned to engage an extension on the other pawl member.

Referring more in detail to the figures of the drawing, a suitable support 10 is provided through which extends a rotatable shaft 11. On this shaft 11 adjacent the support 10 is a ratchet wheel 12 fixed thereto by means of the keys 13 as shown. Between the ratchet wheel 12 and support 10 and preferably adapted to oscillate about a bearing 14 formed on one of the supporting members 10 is an arm 15 which at an intermediate point is attached to a connecting rod 16. By any suitable means, not shown, this connecting rod 16 may be reciprocated so that the oscillating arm 15 may be oscillated through a constant angle with each 95 movement of the rod 16.

On the outer end of this oscillating arm 15 is an intermediate pawl member 17 which is suitably pivoted about a pin 18 in the oscillating arm 15. Near the lower 100 end of this intermediate pawl member 17 is a small pawl member 19 pivoted to the intermediate member at 20 and adapted at its outer end to directly engage the teeth of the ratchet wheel 12. Preferably, and 105 as shown, the two pawl members 17 and 19 are held in normal operative positions by means of a spring 21 engaging the pawl members 17 and 19 and preferably surrounding the pivot 20. A pin 22 in the 110

intermediate pawl member 17 prevents the spring 21 from moving the pawl member 19 beyond a proper limited position relative to pawl 17 and a slight projection 23 on the pawl member 19 cooperating with a pin 24 in pawl 17 prevents the pawl member 19 from being deflected beyond a proper amount in the opposite direction.

It will be seen from the above construction that with reciprocations of the connecting rod 16 and oscillations of the arm 15 the pawl 19 will be made to engage successive teeth in the ratchet wheel 12 and advance the ratchet wheel 12 and the rotating shaft 11 through small angles with each reciprocation of the arm 15. As it is frequently desirable to vary the rotative movement of the ratchet wheel 12 and shaft 11 to effect variable feeds or other functions, special means have been provided to restrict the rotative movement of this ratchet wheel 12 while the oscillating arm 15 may continue to operate through the same distance. These means comprise an adjustable stop 25 which may be positioned anywhere in the arcuate slot 26 formed in one of the supporting members 10.

This adjustable stop 25 has a pin 27 outstanding therefrom adapted to be engaged by an integral extension 28 formed on the intermediate pawl member 17. By positioning the adjustable stop 25 at any predetermined point in the arcuate slot 26, the pin 27 may be made to engage and oscillate this intermediate pawl member 17 at any point in the stroke of the oscillating arm 15. As soon as the intermediate pawl member 17 is engaged by this pin 27, the intermediate pawl member 17 is oscillated about its pivot 18 while the other pawl member 19 remains in contact with a tooth of the ratchet wheel 12. Thus as the pawl 19 remains in contact with the tooth of the ratchet wheel 12, the two pawl members 17 and 19 are relatively oscillated about the pivot 20 on the intermediate pawl member 17. This oscillating movement of the two pawl members is sufficient to move the pivot 20 to the opposite side of a line extending from the point of engagement with the pawl member 19 with the teeth of the ratchet wheel 12 and the pivot 18 for the intermediate member 17 therefore no further movement of the ratchet wheel 12 will take place but the pawl member 19 will continue to oscillate about the intermediate member thus effectively stopping further advancing movement of the ratchet wheel 12 and shaft 11.

To hold the ratchet wheel 12 in its advanced rotative position another pawl member 29 is provided preferably pivotally mounted on the supporting member 10 and engaging another one of the teeth of the ratchet wheel 12. It will be seen therefore

that a mechanism has been provided which will permit a ratchet wheel 12 to be advanced variable predetermined small distances by means of the oscillating arm 15 while the oscillating arm continues to oscillate throughout a constant angular distance.

What I claim is:

1. A ratchet and pawl mechanism comprising in combination, a ratchet wheel, an oscillating arm having a pawl thereon adapted to engage and rotate the ratchet wheel, an intermediate pawl member on the arm, an extension on the intermediate pawl member, and adjustable means engaging said extension and causing said intermediate pawl to be oscillated and oscillating the pawl out of driving engagement with the ratchet wheel at any predetermined point in the stroke of the oscillating arm.

2. A ratchet and pawl mechanism comprising in combination, a ratchet wheel, an oscillating arm having a pawl thereon adapted to engage and rotate the ratchet wheel, said pawl comprising two pivotally connected members having spring means to hold them in operative relative position, an extension on one of said members, and adjustable means engaging said extension adapted to oscillate the other member out of driving engagement with the ratchet wheel at any predetermined point in the stroke of the oscillating arm.

3. A ratchet and pawl mechanism comprising in combination, a ratchet wheel, an oscillating arm having a pawl thereon adapted to engage and rotate the ratchet wheel, said pawl comprising two pivotally connected members having spring means to hold them in operative relative position, an extension on one of said members, adjustable means engaging said extension adapted to oscillate the other member out of driving engagement with the ratchet wheel at any predetermined point in the stroke of the oscillating arm, and means to clamp the adjustable means in any desired position.

4. A ratchet and pawl mechanism comprising in combination, a ratchet wheel, an oscillating arm having a pawl thereon adapted to engage and rotate the ratchet wheel, said pawl comprising two pivotally connected members having spring means to hold them in operative relative position, an extension on one of said members, and an adjustable stop adapted to engage said extension whereby the two pawl members are relatively oscillated about each other and about the oscillating arm and are disengaged from driving relation with the ratchet wheel.

In testimony whereof, I hereto affix my signature.

WILLARD T. SEARS.
